O. H. TORGERSEN,
CIRCUIT BREAKER,
APPLICATION FILED JUNE 11, 1917.

Patented Dec. 10, 1918.

John Enders,

INVENTOR
Orne H. Torgersen,

Robert Burns
ATTORNEY

UNITED STATES PATENT OFFICE.

ORNE H. TORGERSSEN, OF CHICAGO, ILLINOIS, ASSIGNOR OF ONE-HALF TO FRANK A. E. HOLMES, OF CHICAGO, ILLINOIS.

CIRCUIT-BREAKER.

1,287,522.

Specification of Letters Patent. Patented Dec. 10, 1918.

Application filed June 11, 1917. Serial No. 173,988.

To all whom it may concern:

Be it known that I, ORNE H. TORGERSSEN, a citizen of the United States of America, and a resident of Chicago, in the county of Cook, State of Illinois, have invented certain new and useful Improvements in Circuit-Breakers, of which the following is a specification.

This invention relates to that type of circuit breakers in which the attainment of a predetermined high pressure in an associated compressed air apparatus, the circuit of the operating electric motor will be automatically opened, and the present improvement has for its object:—

To provide a simple and efficient structural formation and association of parts by which the circuit breaker is automatically opened in a rapid and effective manner by a predetermined increase in the air pressure in the system, and with which the closing of such circuit by the operator can be readily effected as occasion may require, all as will hereinafter more fully appear.

25 In the accompanying drawing:

Figure 1, is a plan view of an automatic circuit breaker involving the present improvement.

Fig. 2, is a sectional elevation of the same, 30 with the circuit breaking parts shown in a closed condition.

Fig. 3 is a fragmentary sectional elevation, with the circuit breaking parts shown in an open condition.

35 Similar reference numerals indicate like parts in the several views.

Referring to the drawing, 1 designates a supporting bracket adapted for convenient attachment to the frame of the compressed air apparatus with which the present application is associated.

2 designates the casing of a pneumatic motor fixedly associated with the bracket 1, and preferably comprising a pair of cup-shaped sections between which a piston diaphragm 3 is secured in any usual and suitable manner.

4 designates a vertical stem or post fixed centrally on the upper section of the motor casing 2 and having its upper end screw

threaded for the reception of the adjusting nut 5 of the upper adjustable abutment collar 6 of the mechanism.

7 designates the companion lower abutment collar sliding upon the lower portion 55 of the vertical stem 4 with its upper surface adapted to have operative engagement with the hereinafter described rock arm or lever of the switch latching mechanism. Said lower abutment collar 7 has operative engagement with the piston diaphragm 3 by means of a circular bearing head or disk 8 resting upon the upper surface of said diaphragm and provided with a series of studs 9 extending through orifices in the upper section of the motor casing 2 and bearing against the underside of the abutment collar 7 to effect an upward movement of said collar in unison with that of said diaphragm.

10 designates a spring, preferably of the spiral compression type shown, arranged to encircle the aforesaid stem 4 with its respective ends abutting against the upper and lower collars 6 and 7 aforesaid. The tension stress of said spring 10 is capable of adjustment by the adjusting nut 5 aforesaid, so that a predetermined pressure on the underside of the diaphragm 3 will compress said spring to the required extent to cause a release of the switch release mechanism now to be described.

11 designates a switch carrying head fixedly secured to the frame 1 and formed with a bore or passage preferably in right-angle relation to the vertical stem 4 above described.

12 designates an annular bushing fixedly secured in outer portion of the bore of the head 11 aforesaid, and having an inturned stop flange 13 at one end to limit the movement of the hereinafter described push button 29 under the influence of its spring 21.

14 designates a companion bushing fixedly secured in the inner portion of the bore of the head 11 aforesaid, and formed with an axial guide orifice for the sliding contact bar hereinafter described.

15 designates a pair of spring contact fingers of any usual form secured in an insulated manner on one end of the bushing 100

- 14 aforesaid, and connected in any usual manner in the circuit of the apparatus to be controlled. Said contact fingers are disposed at opposite sides of the axial orifice 5 of the bushing 14 and in the path of the above mentioned sliding contact bar to have electrical contact therewith and close the circuit therethrough when said contact bar is in its outer position.
- 10 16 designates a sliding contact bar above referred to having movement in the aforesaid axial guide orifice of the bushing 14 and adapted when moved to the right in the drawing to have contact with both terminals 15 15 aforesaid, and close the electric circuit between the same.
- 15 17 designates a spring having engagement with an outward extension or stem 18 of the contact bar 16 and adapted to move and hold 20 the same in a normal position out of contact with the terminals 15, 15 aforesaid. In the construction shown in Figs. 2 and 3, the said spring 17 and the stem 18 of the contact bar 16 are arranged within a casing 19 carried 25 by the push button now to be described.
- 20 21 designates a push button slidably arranged in the aforesaid bushing 12 and in aligned relation to the contact bar 16 aforesaid, and 21 designates a spring individual to 30 said push button and adapted to move and yieldingly hold said push button to and at a position normally to the left in the drawing. In the construction shown, the aforesaid contact bar 16 is capable of movement 35 to the left to break the contact of the electric circuit independent of the push button, through the instrumentality of its individual actuating spring 17 aforesaid, so that friction due to its sliding contact is the sole impedance to its free movement, and in consequence its action in connection with the associated latch bolt mechanism hereinafter described, is very sensitive.
- 22 22 designates a notch or recess formed in 40 the side of the contact bar 16 and adapted for engagement with a latch bolt hereinafter described and so that the contact bar 16 will be held in a contacting position between the terminals 15, 15 until the holding engagement 45 of said latch bolt with the contact bar 16 is released.
- 23 23 designates the latch bolt above referred to, having a sliding movement in an orifice formed therefor in the inner bushing 50 14 aforesaid, with its upper end adapted for holding engagement in the notch 22 of the contact bar 16 aforesaid. At its lower end said latch bolt 23 is provided with an enlarged head for pivotal attachment to an 55 operating lever arranged as follows:—
- 24 24 designates a rock arm or lever pivoted near its midlength to standards on the supporting frame 1, with its outer end pivotally attached to the latch bolt 23 above described,

and with its inner end resting upon and 65 operatively engaged by the lower abutment collar 7 heretofore described.

25 designates a spring associated with the rock lever 24 and adapted to move the same in a direction to engage the associated latch 70 bolt 23 with the sliding contact bar 16 aforesaid.

With the present mechanism, the operator by pushing the push button 20 inwardly moves the contact bar 16 between the terminals 15, 15 to close the circuit between the same, and the contact bar 16 is held in such position by the automatic engagement of the latch bolt 23 with the notch 22 of the said contact bar. Such condition of the mechanism will prevail until such times as a predetermined high pressure is attained in the compressed air apparatus with which the present mechanism is associated. With the attainment of such pressure the piston dia- 80 phragm 3 is forced upward and through the lower abutment collar 7 and rock lever 24 causes the latch bolt 23 to move out of engagement with the notch 22 of the contact bar 16, leaving the same free to be moved by 90 its spring 17 out of its contacting engagement with the terminals 15, 15 and thus cause a break in the circuit of the operating electric motor of the compressed air apparatus.

Having thus fully described my said invention, what I claim as new and desire to secure by Letters Patent, is:—

1. In an automatic circuit controlling mechanism of the type herein described, the combination of a supporting bracket, a 100 motor casing associated with said bracket and comprising a pair of cup shape sections and a piston diaphragm disposed between said sections and adapted to be moved in one direction by pneumatic pressure, a 105 guide stem fixedly associated with said casing, an adjustable abutment on the upper end of said stem, a movable abutment collar on the lower portion of said stem, a spring 110 interposed between said abutments and adapted to impart movement to the piston diaphragm in a direction opposite to that effected by pneumatic pressure, a head having bearing on the piston diaphragm and operatively connected to the aforesaid movable abutment collar by a plurality of studs passing through the motor casing, a rock- 115 lever operatively associated with said movable abutment collar, and a self opening circuit breaking mechanism having a latching 120 means operatively connected to said rock-lever, substantially as set forth.

2. In an automatic circuit controlling mechanism of the type herein described, the combination of a supporting bracket, a 125 motor casing associated with said bracket and comprising a pair of cup shape sections and a piston diaphragm disposed between

said sections and adapted to be moved in one direction by pneumatic pressure, a guide stem fixedly associated with said casing, an adjustable abutment collar on the upper end 5 of said stem, a movable abutment collar on the lower portion of said stem, means for effecting an adjustment of said collar, a spring associated with the aforesaid collars and adapted to impart movement to the aforesaid 10 piston diaphragm in a direction opposite to that effected by pneumatic pressure, a head having bearing on the piston diaphragm and

operatively connected to the movable abutment collar by a plurality of studs passing through the motor casing, a rock-lever operatively associated with said movable abutment collar, and a self-opening circuit breaking mechanism having a latching means operatively connected to said rock-lever, substantially as set forth. 15

Signed at Chicago, Illinois, this 7th day of June, 1917.

ORNE H. TORGERSEN.
